(57) **CLAIM**

I claim the ornamental design for a skid loader attachment for removing snow from a roof, as shown and described.

DESCRIPTION

FIG. 1 is a rear, top and side perspective view of the skid loader attachment for removing snow from a roof embodying the design of the present invention.

FIG. 2 is an end elevational view thereof, the opposite end being identical to the end shown.

FIG. 3 is a rear elevational view thereof.

FIG. 4 is a top plan view thereof.

FIG. 5 is a front elevational view thereof; and,

FIG. 6 is a bottom plan view thereof.
